UNITED STATES PATENT OFFICE.

ROSCOE TENNY, OF DAVID CITY, NEBRASKA.

DESIGN FOR A HIGHWAY ADVERTISING AND DIRECTING SIGN.

59,693.

Specification for Design.

Patented Nov. 15, 1921.

Application filed January 17, 1921. Serial No. 438,019. Term of patent 7 years.

To all whom it may concern:

Be it known that I, ROSCOE TENNY, a citizen of the United States, residing at David City, in the county of Butler and State of Nebraska, have invented a new, original, and ornamental Design for a Highway Advertising and Directing Sign, of which the following is a specification, reference being had to the accompanying drawing, forming part thereof.

The figure is a face view of a highway advertising and directing sign.

The surface shading indicates contrasting colors.

I claim:

The ornamental design for a highway advertising and directing sign as herein shown and described.

In testimony whereof I affix my signature.
ROSCOE TENNY.
